UNITED STATES PATENT OFFICE.

HENRY G. VOIGHT, OF NEW BRITAIN, CONNECTICUT, ASSIGNOR TO RUSSELL & ERWIN MANUFACTURING COMPANY, OF NEW BRITAIN, CONNECTICUT, A CORPORATION OF CONNECTICUT.

DOOR-CHECK CUSHION-STOP.

1,024,465.

Specification of Letters Patent. Patented Apr. 23, 1912.

Application filed July 19, 1911. Serial No. 639,263.

To all whom it may concern:

Be it known that I, HENRY G. VOIGHT, a citizen of the United States, residing at New Britain, Hartford county, State of Connecticut, have invented certain new and useful Improvements in Door-Check Cushion-Stops, of which the following is a full, clear, and exact description.

My invention relates to an improved adjustable buffer device for door checks and closers and relates particularly to that type of a check carried by a bracket, the latter being connected in turn to the door casing and the check operating as a stop limiting the outward movement of the door.

In the accompanying drawings, Figure 1 is a plan view of my invention as set up ready for use. Fig. 2 is a detail view.

1 represents part of a door check and 20 closer.

2 represents a controlled lever arm. 2^a represents an adjustable link connecting the free end of said lever arm 2 with a door 3.

4 represents a bracket arranged to be secured to a part of a door casing 3^a. The part 1 is connected to the bracket 4 in any suitable manner. The bracket 4 carries a spring controlled plunger 5 having a buffer head 6.

30 7-7 are guides for the plunger 5.

8 is a spring arranged to press the plunger 5 and buffer head 6 outwardly. The head 6 is preferably screw threaded on the plunger 5 for adjustment.

35 9 is a check nut constituting one simple means for holding the buffer head 6 locked in any particular adjusted position.

The buffer head 6 is arranged in a plane where it will be engaged by the lever arm 2 when the door has been opened to the desired extent where it is desired to check the further opening movement thereof. When the arm hits against the buffer head 6, the latter is re-pressed against the tension of

40 45 the spring 8 so as to bring the lever arm 2 to a stop, the stopping of said lever arm being cushioned, thereby greatly reducing the danger of breakage of the arm 2 and

the associated parts as well as reducing the strain upon the fastenings by which the 50 bracket 4 is secured to the casing 3^a.

In Fig. 1 I have shown the normal position of the door check and closer in solid lines, whereas, in dotted lines I have shown the same in the abnormal position in which 55 the door is open.

10 represents a collar mounted on the plunger 5, which constitutes an abutment against which one end of the spring 8 presses, the opposite end of the spring 60 pressing against the rear abutment 7. The collar 10 may be pinned upon the plunger 5 or otherwise suitably fastened for securing, preferably, adjustable attachment. The buffer head 6 is preferably rounded or 65 suitably shaped to avoid friction upon the arm 2 when the door is fully open.

What I claim is:

1. In a combined door closer and stop, the combination of a bracket secured to a 70 door casing; a door closer casing secured to said bracket and provided with a rotatable shaft; an arm mounted on said shaft and pivotally connected to a door; and a buffer mounted on said bracket in the plane of lateral movement of the closer arm during outward or opening movement of the door and adapted to be engaged by said arm to prevent further outward movement of the door.

2. In a combined door closer and stop, 80 the combination of a bracket secured to a door casing; a door closer casing secured to said bracket and provided with a rotatable shaft; an arm mounted on said shaft and pivotally connected to a door; and a yielding plunger slidably mounted in said bracket and provided with a buffer head extending into the plane of lateral movement of the closer arm during outward or opening movement of the door, and adapted to be engaged by said arm to prevent further outward movement of said door.

HENRY G. VOIGHT.
